DISPLAY SIGN STRUCTURE

William A. Martin, Sweetwater, Tex.

Application February 13, 1948, Serial No. 8,112

1 Claim. (Cl. 40—132)

1

This invention comprises novel and useful improvements in a display sign structure and more particularly pertains to an illuminated sign whereon there may be interchangeably mounted a series of letters or other indicia to provide an attractive advertising display.

The principal object of this invention resides in providing a highly ornamental and attractive, illuminated advertising display sign whereon the message or representation display may be easily varied.

An important feature of the invention resides in the provision of an illuminated sign consisting of a casing having a source of illumination therein combined with a corrugated transparent panel in the front of said illumination, together with transverse supporting ribs secured to the outer surface of said panel for selectively and detachably receiving a plurality of letters or other advertising and display indicia.

A further feature of the invention resides in the provision of an advantageous, simple and novel supporting means for securing and mounting the transparent corrugated panels in the front open end of the sign casing.

A still further feature of the invention resides in the provision of an improved arrangement for forming the transparent panel by means of a plurality of corrugated sheets of transparent plastic together with a readily detachable means for rigidly securing the sheets to the panel support or mounting means.

And a final important feature and object of the invention to be specifically enumerated herein, is to provide an attractive novelty advertising and display sign which may be constructed in any size desired, of inexpensive materials, may be readily changed to vary the message or exhibit displayed, and which shall be highly efficient for the purposes intended.

These, together with various ancillary features and objects of the invention which will later become apparent as the following description proceeds, are attained by this device, a preferred embodiment of which has been illustrated by way of example only in the accompanying drawings, wherein:

Figure 1 is a fragmentary front elevational view of the display sign constructed in accordance with the principles of this invention;

Figure 2 is a vertical transverse sectional view taken through the housing and casing of the illuminated display sign;

Figure 3 is a fragmentary perspective view of a portion of the transparent panel, showing the

2

manner of detachably mounting the display indicia thereon, and taken from the front of the device;

Figure 4 is a fragmentary group perspective view illustrating the construction and manner of assembling a pair of transparent sheets to form the transparent corrugated panel and for detachably securing the same to the mounting and supporting means of the device;

Figure 5 is a fragmentary vertical transverse sectional detail view taken upon an enlarged scale through a portion of the device and illustrating the construction of the panel supporting and fastening means; and

Figure 6 is a perspective view of one of the sign indicia, illustrating the manner of attaching the same to the transparent panel.

Referring now more specifically to the accompanying drawings, wherein like numerals designate similar parts throughout the various views, attention is directed more particularly to Figure 2, wherein it will be seen that the illuminated display sign embodying the principles of this invention consists of a generally rectangular housing or casing 10, having a closed back wall 12, and an open front wall 14, within which is rigidly secured as by welding 16, an L-shaped channel member 18 constituting a frame for receiving and supporting a transparent plastic panel of any suitable construction indicated generally by the numeral 20.

As will be clearly seen by reference to Figure 2, a plurality of electric light bulbs 22 of any desired construction are supported by the rear wall 12 of the casing, and extend forwardly into close proximity to transparent panel 20, it being understood that any conventional type of electrical circuit, not shown, may be employed for activating the light bulbs 22.

Likewise secured upon the rear wall 12, as indicated best in Figure 5, are a plurality of panels 20 and securing means, one of which is illustrated in Figure 5, and which as shown consists of a rod 24 whose horizontally and forwardly extending end is externally threaded as at 26, and which is provided with a preferably integral cruciform-shaped face 28 which is detachably secured to the inner surface of the rear wall 12 as by fastening bolts 30. The end of the screw-threaded portion 26 of the rod 24 preferably terminates in proximity to the rear or inner surface of the transparent panel 20. Adjustably secured upon the rod 24 is the internally threaded sleeve 32. It is contemplated that this sleeve will be adjusted longitudinally of the rod

24 upon the threads 26 thereof in order to position the outward end of the sleeve in abutment against the inner or rear surface of the transparent panel 20 for bracing and mounting the same. A headed screw or other fastening means 34 of any desired construction extends through suitable openings in the panel 20 whereby the latter is clamped tightly against the outer end of the sleeve 32, it being understood that the screw is threaded into the internally threaded 10 bore of the sleeve 32.

It will thus be seen that by means of the adjustable fastening and mounting element, the transparent panels may be readily mounted in the casings or housings 10 of different thicknesses, and when so mounted the panel is secured to the end of the sleeve 32, and also drawn tightly against the upwardly turned flange 36 of the L-shaped frame 18.

Attention is next directed to Figures 3 and 4 20 for a better understanding of the construction of the transparent panel. The latter, of course, can be made from any suitable material, and as shown is preferably corrugated with vertical 25 grooves in order to stiffen the panel and give the same greater structural strength. Secured in any suitable manner to the corrugations 33 of the panel, and extending horizontally or transversely thereacross, are a plurality of parallel outwardly and upwardly inclined ribs 40 constituting fastening means upon which may be detachably hung indicia of any suitable type such for example as solid or if desired hollow or other indicia means such as the printed or script letters 42, shown in Figures 1, 3 and 6. As will be seen by particular reference to Figure 6, the rear side of the indicia 42 is provided with suitable slot 44 appropriately shaped and proportioned for detachable engagement upon the ribs 40 whereby the indicia may be readily applied to but easily removed from the supporting ribs as clearly illustrated in Figures 2 and 3.

As will be more clearly apparent from reference to Figure 4, it is contemplated that the transparent panel 20 may be formed of any desired size by detachably securing together a plurality of transparent, vertically corrugated sheets of transparent plastic, two such sheets being indicated in Figure 1 at 46 and 48. By assembling a plurality of sheets, obviously the same standard forms may be employed to produce illuminated advertising signs of any desired size and shape. In order to conveniently assemble the sheets to form the transparent panel 20, and also to remove one or more sheets to obtain access to the interior of the casing 10, a suitable detachable connection is provided with the fastening screw 34 and sleeve 32, whereby the sheets may be applied or removed without the necessity for removing the screw. This means preferably consists of a marginal slot 50 formed in the edge of the sheet 46, whereby the sheet may be slid sidewise upon the shank of the screw 34 between the head thereof and the end of the sleeve 32; while the sheet 48 adjacent its marginal edge is provided with a keyhole slot 52 whereby the enlarged portion may be readily passed over the head 34, and the sheet then moved vertically until the narrow portion of the slot is engaged upon the stem of the screw and whereby the same is prevented from unintentional passage therefrom over the head thereof. This arrangement has been found to be satisfactory since the

5 overlapping corrugated sheets may be readily applied by giving the inner sheet a lateral motion to engage the same, and by giving the outer sheet a vertical motion, whereby the corrugations of the sheet do not prevent their attachment to the fastening screw. It should be here noted that the fastening rods 24 are not merely applied to the ends of the sheets 46 and 48, but may be applied at various intervals throughout their area to give the necessary rigid reinforcement required for large signs.

From the foregoing, it is felt that the manner of constructing and utilizing the invention together with the advantages arising therefrom will be readily understood and further explanation is believed to be unnecessary. However, since numerous modifications will readily occur to those skilled in the art after a consideration of the foregoing specification and accompanying drawings, it is not intended to limit the invention to the exact construction shown and described, and all suitable modifications and equivalents may be resorted to falling within the scope of the appended claim.

Having thus disclosed and described the invention, what is claimed as new is as follows:

A display sign structure including a casing having a back wall, an open front and a source of illumination therein, a transparent corrugated panel at the open end of said casing, mounting means in said casing carried by said back wall and supporting said panel, a plurality of parallel upwardly inclined ribs secured to said panel and a series of indicia elements with inclined supporting notches for mounting upon said ribs, said mounting means including a threaded rod having a base plate secured to said back wall, an internally threaded sleeve on said rod, the forward end of said sleeve engaging the inner 40 surface of said panel, an L-shaped frame secured to said front wall, and a screw extending through said panel for attachment to said sleeve and securing said panel against said L-shaped frame, said panel including a plurality of overlapping corrugated sheets, and means for detachably positioning overlapping adjacent edges of said sheets under the head of said screw, said means including a keyhole slot in the edges of one sheet, having an opening of sufficient diameter at one end and of insufficient diameter at the other end to pass the screw head, and a marginal slot in the edges of the other sheet to receive the screw but prevent passage of the head.
